UNITED STATES PATENT OFFICE.

DAVID COCKBURN AND DONALD MACNICOLL, OF CARDONALD, NEAR GLASGOW,
SCOTLAND.

POSITIVELY-CONTROLLED MANEUVERING AND EMERGENCY SHUT-OFF VALVE.

Application filed September 12, 1921. Serial No. 500,146.

To all whom it may concern:

Be it known that we, DAVID COCKBURN and DONALD MACNICOLL, subjects of the King of the United Kingdom of Great Britain and 5 Ireland, and residing at Clydesdale Engineering Works, Cardonald, near Glasgow, Scotland, having invented a certain new and useful Improvement in Positively-Controlled Maneuvering and Emergency Shut-Off 10 Valves, of which the following is a specification.

This invention relates to emergency operating devices for positively controlled maneuvering and emergency shut off valves of 15 the type which are dependent for operation on the fall in the pressure of liquid, for example oil in an oil system, or on the operation of hand or other controlling gear.

According to the invention there is provided a cylinder in communication with the main valve chest and with an auxiliary valve chest, movable in which cylinder is a piston normally exposed to fluid pressure over a greater area on one side than on the other 25 side, said piston being operatively connected to the main valve operating mechanism. The auxiliary valve chest is provided with three ports, one port leading to the source of pressure fluid supply and normally in communication with the first side of the piston, a second port adapted, when open, to permit communication between the first side of the piston and the atmosphere, and a third port adapted, when open, to permit communication 30 between a chamber adjacent to the unexposed area of the second side of the piston and the atmosphere. A valve element is provided with two valve faces, the first face adapted to control the second port and the 35 second face adapted to control the third port. The arrangement is such that in the operation of the emergency gear the said valve element moves to open the second port and to close the third port, the first side of 40 the piston is brought into communication with the atmosphere and the full area of the second side of the piston is rendered subject to fluid pressure whereby the piston is constrained to move in the direction corresponding to the closing movement of the main 45 valve.

The invention is illustrated in the accompanying drawing in which Fig. 1 is a section of the main valve chest and associated parts

and Fig. 2 a section of the auxiliary valve 55 chest.

Referring to the drawing, the emergency cylinder 1 is in continuous communication with the main valve chest 10. Movable in the cylinder 1 is a piston 2 which is normally exposed to steam pressure over its full area on the under side but is exposed to steam pressure over less than its full area on the upper side, the exposed area being reduced by the diameter of a chamber 3 provided with a valve face 4 engaging a face 5 on the piston 2. The piston 2 is thus normally held in raised position and escape of steam from the cylinder 1 is prevented. A port 1^a connects the main valve chest 10 with the 60 upper end of the cylinder 1. The piston 2 is operatively connected to the operating mechanism for the valve 26 by a rod 6, a bell crank lever 7, a link 8 and a main lever 9. Connected to the main valve chest 10 is 65 an auxiliary valve chest 11 communicating by way of a passage 12 with the source of steam supply and provided with three ports 13, 14, 15. The port 13 leads to the passage 12 and is normally in communication with 70 the under side of the emergency piston 2 by way of a cylindrical guide 11^a. The port 14 is adapted, when open, to permit communication between the under side of the piston 2 and the atmosphere by way of a pipe 16. 75 The port 15 is adapted when open to permit communication between the chamber 3 and the atmosphere. Controlling the ports 14, 15 is a valve element 17 depending for operation 80 on variation of the oil pressure or on hand or other control gear and provided with valve faces 14^a and 15^a. The face 14^a is adapted to control the port 14 communicating with the under side of the piston and the face 15^a is adapted to control the port 15 85 communicating with the chamber 3. The arrangement is such that, when the pressure in the oil system falls, the valve element 17 moves to open the port 14 and to close the port 15, whereby the under side of the piston 2 is brought into communication with the atmosphere, and the piston 2 is caused to move in the direction corresponding to the closing movement of the main valve 26 so that the faces 4 and 5 separate and the full 90 area of the upper side of the piston 2 is rendered subject to steam pressure, without leakage of steam through the port 15. 95 100 105

Cooperating with the cylindrical guide 11^a in the auxiliary valve chest is a piston element 18 which normally permits leakage of steam through the guide towards the under-
5 side of the piston 2 and exerts no effort to move the valve element 17 so long as the face 14^a is seated, the pressures on both sides of the piston element 18 being equal. When the port 14 is open, the steam acting on the
10 piston element 18 urges the valve element 17 away from the port 14 and thus continues the movement of said valve element after the face 14^a vacates the zone influenced by the steam passing through the port 14.

15 The piston element 18 is provided with a valve face 13^a adapted to seat on the port 13 so as to interrupt the supply of steam through the port 12.

20 The valve element 17 may be conveniently operated by hand or other control gear.

In the construction shown, the valve element 17 is actuated by a piston 19 reciproca-
25 ble in a cylinder 20 the underside of which communicates with the oil system.

25 The piston is connected to the element 17 through a yoke 21 and levers 22 fulcrumed at 23 and connected at 24 and 25 respectively to the yoke 21 and to the element 17.

30 On the stem 17¹ of the valve element 17 is loosely fitted a bush 17² which assists in balancing the valve element 17.

35 On the opening movement of the valve element 17 there is an effort on top of said element, there being fluid in the space above the latter.

Normally the element 18 should sustain the fluid pressure but if it should chance to bind it will of course be of no assistance in maintaining a balance. The bush 17², how-
40 ever, functions as a balancing bush, i. e., in conjunction with the valve element 17 forms a balanced system. Should the bush 17² bind, the stem 17¹ of the valve element 17 is still free to slide through the bush 17² so that the valve element 17 can function even though unbalanced.

We claim:

1. In emergency valve gear, in combination with main valve and operating mechanism therefor, a piston operatively connected to said mechanism, said piston normally exposed to fluid pressure over a greater area on one side than the other, a cylinder in which said piston is movable, a chamber adjacent to the unexposed portion of the second side of said piston, an auxiliary valve chest having communication with said cylinder and provided with a port leading to the source of pressure fluid supply and normally in communication with the first side of said piston, a second port adapted, when open, to permit communication between the first side of said piston and the atmosphere, and a third port adapted, when open, to permit communication between said chamber

and the atmosphere, and a valve element provided with a valve face adapted to control the second port and a second face adapted to control the third port, said valve movable, during the operation of said mechanism, to open the second port and close the third port, to bring the first side of said piston into communication with the atmosphere and render the full area of the second side of said piston subject to fluid pressure whereby said piston is constrained to move in the direction corresponding to the closing movement of said main valve.

2. In emergency valve gear, in combination with a main valve and operating mech- 80

anism therefor, a piston operatively connected to said mechanism, said piston normally exposed to fluid pressure over a greater area on one side than the other, a cylinder in which said piston is movable, a chamber adjacent to the unexposed portion of the second side of said piston, an auxiliary valve chest having communication with said cylinder and provided with a port leading to the source of pressure fluid supply and normally in communication with the first side of said piston, a second port adapted, when open, to permit communication between the first side of said piston and the atmosphere, and a third port adapted, when open, to permit communication between said chamber and the atmosphere, a valve element pro- 85

vided with a valve face adapted to control the second port and a second face adapted to control the third port, said valve movable, during the operation of said mechanism, to open the second port and close the third port, to bring the first side of said piston into communication with the atmosphere and render the full area of the second side of said piston subject to fluid pressure whereby said piston is constrained to move in the direction corresponding to the closing movement of said main valve, a cylindrical guide in said chest, and a piston element 90

cooperating with said guide and controlling communication between the source of fluid pressure supply and the first side of said piston, said element being independent of and abutting against said valve element. 110

3. In emergency valve gear, in combination with a main valve and main operating mechanism therefor, a piston operatively connected to said mechanism, said piston normally exposed to fluid pressure over a greater area on one side than the other, a cylinder in which said piston is movable, a chamber adjacent to the unexposed portion of the second side of said piston, an auxiliary valve chest having communication with said cylinder and provided with a port leading to the source of pressure fluid supply and normally in communication with the first side of said piston, a second port adapt- 120

ed, when open, to permit communication between said chamber and the atmosphere, and a third port adapted, when open, to permit communication be- 130

tween the first side of said piston and the atmosphere, and a third port having an extension and adapted, when open, to permit communication between said chamber and the atmosphere, a valve element having a stem and provided with a valve face adapted to control the second port and a second face adapted to control the third port, said valve element movable, during the operation 10 of said mechanism, to open the second port and close the third port, to bring the first side of said piston into communication with the atmosphere and render the full area of the second side of said piston subject to fluid

pressure whereby said piston is constrained 15 to move in the direction corresponding to the closing movement of said main valve, and a bush in which the stem of said valve element is loosely fitted and which bush is movable in an extension of the third port. 20

In testimony whereof we have signed our names to this specification in the presence of two subscribing witnesses.
